METHOD OF TREATING MINERAL OILS

Stanislaw Pilat and Marian Godlewicz, Lemberg,
Poland, assignors to Shell Development Com-
pany, San Francisco, Calif., a corporation of
Delaware

Application January 30, 1934, Serial No. 708,988
In Poland February 6, 1933

16 Claims. (Cl. 196—13)

This invention pertains to a method of separating mineral oils into fractions of different physical and/or chemical properties, and is particularly concerned with the treatment of relatively viscous mineral oils, petroleum residues, lubricating oil distillates, coal tar and coal tar oils, and other hydrocarbon mixtures, with gases under pressure, said pressure being insufficient for liquefaction of the gases in question.

While a number of extraction methods employing various liquids as selective solvents for extracting mineral oils are well known, we have discovered that the separation of oils into fractions may be accomplished without making use of liquid solvents, but by regulating the degree of saturation of the oil with a gaseous substance. Considerable advantages are inherent in our method of treatment, one of which is that relatively low pressures (far below liquefaction pressures of said gaseous substances) and ordinary or elevated temperatures (not exceeding 200° C.) may be employed in carrying out the process of our invention. No chemical changes are involved in separating mineral oils by the method of our invention, the treatment being of a physical and not chemical type.

Briefly, the invention consists of introducing into a mineral oil a gas under a superatmospheric pressure until a concentration is reached at which the oil separates into two phases of different specific gravities. Relative quantities and compositions of the oil portions in the phases are regulated by maintaining suitable treating temperatures and pressures, as well as by selecting or regulating the composition of the gaseous treating agent; as gaseous treating agents may be used: methane, ethane, carbon dioxide, hydrogen, water-gas, dry natural gas, or any other substance or a mixture of substances, which is gaseous at the temperature and pressure employed and which is capable, on being introduced in the gaseous state under a superatmospheric pressure into the oil being treated, to cause the separation of the same into two phases of different properties.

The process can be modified by dissolving the oil to be treated in a suitable solvent which may be of the type of known deasphaltizing agents, such as normally liquid or liquefied hydrocarbons, as propane, propylene, normal or iso-

butanes, butylenes, normal or iso-pentanes, hexanes, or their mixtures, light straight run naphthas, or other light aromatic-free fractions of a mineral oil; or said solvent may be chosen 5 from a group of what are known as selective or naphthenic solvents, such as liquid SO₂, furfural, nitrobenzene, "Chlorex" ($\beta\beta'$ dichloroethyl ether), cresylic acid, phenol, aniline, and a large number of others, their mixtures, or solutions 10 with diluents; we also found, that in practicing our invention auxiliary treating agents of the type of oil decolorizing agents, such as fuller's earth, naphthalene, phenanthrene, dinitrobenzene, and the like, may be advantageously used 15 either instead of or in conjunction with deasphaltizing agents and/or selective solvents described hereinbefore.

In carrying out our invention in practice we prefer to dissolve the mineral oil distillate or residue to be treated in a deasphaltizing agent or in a naphthenic solvent or in a mixture of both, although our process is applicable in treating undissolved mineral oils. The purpose of dissolving the oil in a solvent is to modify the fractionating effect of the gaseous treating agent, because we found that compositions of the fractions obtained by our method of treating an oil, after first dissolving the oil in a solvent, are somewhat different from those obtained from 20 undissolved oils; operating conditions, such as temperatures and pressures, under which a gaseous treating agent is introduced into the oils being separated into fractions, are also affected by the use of either deasphaltizing or other selective solvents in conjunction with our treatment.

In the preferred form of our invention a solvent is usually added to the oil in such quantity as substantially to saturate the oil without causing 25 it to separate into two phases at the temperature used in our treatment. The dissolved oil is then contacted with a gaseous treating agent under pressure, which is lower than the liquefaction pressure of the agent at the corresponding temperature, to cause this agent to dissolve in the oil solution and saturate this solution with accompanying separation of a second heavier phase. The light and heavy phases produced in this manner may be separated by settling or in some other manner, without changing 30 35 40 45 50

their compositions, and then separately treated to remove the solvents from the oil portions. If, however, the oil contains, as most of the distillation residues do, certain undesirable asphaltic or resinous materials, it is preferable in many cases to precipitate these materials first by dissolving the oil in a deasphalting agent, separate the precipitate from the oil solution and then treat the latter in accordance with our invention.

The above-described steps are schematically illustrated in the accompanying drawing, in which 1 is a source of mineral oil to be treated; 2 is a source of a gaseous treating agent, such as methane, ethane, natural gas, etc., maintained under a suitable pressure; 3 is a source of a deasphalting solvent, such as liquid propane, butane, etc.; 4 is a source of a naphthenic or modifying solvent, such as liquid SO_2 , furfural, etc., several of such sources being provided if several solvents are to be employed in the process; and 5 is a mixing and settling vessel, adapted to withstand the pressures employed in the process, and provided with valved inlet lines for introducing material from each of the above-named sources, and with a valved outlet 6.

The initial oil from the source 1 is fed into the vessel 5 by means of a pump 7, after which the valve 8 is closed. In the preferred embodiment of the invention, about three to ten volumes of the liquid deasphalting solvent from the source 3 for each volume of oil are introduced by means of a pump 8', after which the valve 9 is closed. If the initial oil contains asphaltic or resinous materials, these are precipitated by the addition of the solvent, and may be drawn off through the outlet 6 and withdrawn from the process at 10 for recovery of the entrained solvent and/or oil.

The steps described up to this point are known in the prior art. According to the present invention, the oil in the vessel 5, whether or not mixed with the deasphalting solvent, and whether or not the precipitated asphaltic material (if any) has been withdrawn, is mixed with a gas from the source 2 by means of a pump 11 under sufficient pressure to dissolve an effective quantity thereof. The quantity of the gas which is dissolved in the oil, or in the solution of deasphalting solvent, is determined by the solubility of the gas at the temperature of the process and by the pressure on the gas. The pressure is increased by means of the pump 11 until the quantity of the gas dissolved is sufficient to cause the oil to separate into two liquid oil-containing phases of different specific gravities, the pressure being, however, never great enough to cause the gas to be condensed. When pressures below the condensation pressures are insufficient to dissolve sufficient gas, the temperature may be raised to above the critical temperature of the gas by means of a heating coil 12. The more gas is dissolved in the oil, the greater will be the size of the phase of greater specific gravity, and its size and composition can, therefore, be controlled by regulating the pressure.

When sufficient gas has been dissolved in the oil, the valve 13 is closed and the mixture is permitted to stratify; after the mixture has settled, the lower phase is drawn off through the outlet 6 and fed into a separating apparatus 14, where the gas and, if desired, the deasphalting solvent, are separated from the oil contained in the withdrawn phase, the latter being led into receiving

tank 15, and the deasphalting solvent being cooled and condensed in the condenser 17, and returned to the storage tank by means of the pump 19. The gas may be returned to storage by means of the pump 18. The lighter liquid phase remaining in the vessel 5 may then be drawn off and separately treated to remove the gas and solvent.

In addition to, or in place of, the deasphalting solvent, a selective or naphthenic solvent from the source 4 may be introduced into the vessel 5 by means of a pump 20 and valve 21 and mixed with the oil. This solvent may be received from the liquid phases by any desired method in the manner described for the gas and the deasphalting solvent. Auxiliary treating agents, such as fuller's earth, etc., when used, may be introduced into the vessel 5 at 22 and withdrawn therefrom, together with the heavy phase.

Another feature of our invention is that we have found that this method can be used to separate an oil into a series of fractions by successive applications of the already described method of our invention. For example, after separating the primary light phase from the primary heavy phase, after producing these phases by saturating an oil solution with a gaseous treating agent, the separated primary light phase may be contacted with the same gaseous agent and substantially at the same temperature, but under a higher pressure; thus, a further quantity of the agent is forced into the primary light phase and it is caused to separate into two secondary phases of different compositions and gravities, which may be further treated in the already described manner. By repeating this treatment in a series of steps by using progressively increasing pressures, the treated oil can be fractionated into portions having different properties. Referring again to the drawing, this may be effected by closing the valved outlet 6 after the removal of only the heavy liquid phase and introducing an additional quantity of gas by means of the pump 11, the pressure being thereby increased sufficiently to cause an added quantity of gas to be dissolved in the light liquid phase remaining in the vessel, and causing this phase to separate into two new liquid phases of different specific gravities. The valve 13 may then again be closed and after the liquid phases have separated into layers, the heavy layer may be drawn off as before, and fed into the separating apparatus 23, the oil contained therein being fed to the receiving tank 24. After the withdrawal of the second heavy liquid phase, the valved outlet 6 may once more be closed and still more gas introduced into the remaining light liquid phase to cause a still further separation into liquid phases, these steps being repeated as often as desired, depending upon the number of fractions desired. The final light liquid phase is withdrawn from the vessel 5 and separated into oil, gas and solvent components in the separator 25, the oil contained therein being fed to the receiving tank 26. However, instead of subjecting one of the lighter phases (either primary, secondary or any other subsequent one) to a higher pressure than under which the phase was produced, it is also possible to effect the fractionation by maintaining the pressure of the gaseous treating agent substantially constant, and to cause the separation of the oil solution saturated with the agent into two new phases by lowering its temperature. Either of the two methods may be used in a series of separations.

or the two methods may alternate in a series of consecutive treatments.

It may be desirable in a series of consecutive treatments not only to vary the treating conditions, like pressures and temperatures, or the gaseous treating agent, but also to modify the quantity or the composition of the solvent in which the oil is dissolved, by adding, for example, more of the solvent already present in the solution, or by adding a new liquid diluent or other solvent; for instance, liquid SO_2 -benzol solution, "Chlorex" ($\beta\beta'$ dichloroethyl ether) alone or in solution with benzol, or furfural-benzol solution may be used in conjunction with our invention. This may be conveniently effected by introducing a suitable modifying solvent from the source 4 by means of the pump 20.

We found it possible to separate by our method mineral oils into fractions of different chemical characteristics, as indicated, for example, by the temperature-viscosity relationships of different fractions, as well as of different boiling ranges—the manner of separation being dependent on the solvent and/or gaseous treating agent used.

In order to illustrate some of the applications of our invention, the following examples are set forth, without intending, however, to limit this invention to any specific features of these examples.

Example I.—A topped Urycz crude was deasphaltized by dissolving it in about 5-10 volumes of a liquid propane-butane fraction. After the precipitated asphalt was separated, the propane-butane-oil solution was saturated with a dry natural gas under a pressure of about 40 atmospheres at a room temperature. A second heavy dark-colored phase was formed and removed. The light phase was further saturated with the same gas and at the same temperature, but under a pressure of about 100 atmospheres, whereby a new heavy phase was caused to separate, leaving in the secondary light phase a highly deasphaltized oil.

Example II.—A topped crude having specific gravity .9565 at 15° C. and Engler viscosity of 3.03 at 100° C. was dissolved in 10 volumes of a liquid propane-butane fraction. After the separation of precipitated asphaltic substances, a natural gas consisting substantially of methane and ethane (from Daszawa) under a pressure of about 150 atmospheres was introduced into the deasphaltized solution, which was maintained at room temperature. Under these conditions a heavy liquid layer containing 17.08% of the original topped crude sample separated out. The oil separated from the lighter phase had specific gravity .9325, a good color and a viscosity index of 37 (609 sec. Say. at 100° F., 58.6 sec. at 210° F.); a duplicate run produced the corresponding oil having a viscosity index of 41. For comparison, a vacuum distillate from the same crude and having specific gravity .9377 had a viscosity index of 21 (532 sec. Say. at 100° F., 54.9 sec. at 210° F.).

Example III.—A sample of the same topped crude as was used in the Example II was dissolved in 3 volumes of a liquid propane-butane fraction; this was accompanied by precipitation of asphalt, which was removed. The propane-butane-oil phase was saturated with a dry natural gas, consisting substantially of CH_4 and CH_3CH_3 , under a pressure of 75 atmospheres at a room temperature; at this pressure a second phase containing about 33% of original oil, which consisted mainly of heavier and darker-colored

components of the oil, separated out. The phases were separated and the lighter one was then saturated with the same gas under a pressure of 100 atmospheres at the same room temperature; new phases were formed and separated. Altogether the process was repeated four times with the following results:

Fractionation of Urycz topped crude at room temperature

	Percent oil precipitated	At pressure atmospheres	Specific gravity at 15° C.	Viscosity index
15	33	75		
	35	100	.9477	44
	16	125	.9195	53
	1	150		

Example IV.—A heavy cylinder oil distillate of the following characteristics:

Specific gravity at 15° C. .9599
 Viscosity Say. at 100° F. sec. 10,400
 Viscosity Say. at 210° F. sec. 222
 Viscosity index 42

25 was dissolved in 3 volumes of a propane-butane fraction and then saturated with a dry natural gas at room temperature under a pressure of 60 atmospheres. The precipitated layer contained 48% of the original oil. After removing this layer, the lighter phase was subjected to a treatment with the same natural gas under 75 atmospheres, which resulted in the precipitation of 39% of oil; the precipitated oil had a viscosity index of 51 (205 sec. Say. at 210° F.). A further treatment under a pressure of 100 atmospheres produced an oil with viscosity index of 74 (8½% of the original oil).

Depending upon the required properties of oil fractions, the pressure changes in the consecutive stages of our process may be quite small; in many cases a difference of five atmospheres at a substantially constant temperature of the oil produces distinctly different oil fractions; generally, the greater is the change in pressure, the greater is the yield of the heavier phase. On the other hand, a lowering of the treating oil temperature by 10° C., while maintaining a substantially constant gas pressure, may be sufficient in some cases to effect the separation of a gas-saturated oil solution into two phases.

We are aware of the German patent to Metan No. 362,458 disclosing the deasphaltizing effect of dissolving an oil in liquefied normally gaseous hydrocarbons. However, our invention, as described, is directed to the method of fractionating mineral oils by saturating them with gaseous substances incapable of being liquefied under the treating conditions of our process, so that our process may be operated at temperatures, which are beyond the critical temperature of the particular gaseous treating agent which may be used in the process.

We claim as our invention:

1. In a process of separating a hydrocarbon oil into fractions having different properties, the steps of subjecting the oil to the precipitating action of a quantity of a gaseous hydrocarbon treating agent consisting substantially of at least one of the hydrocarbons having less than three carbon atoms per molecule, said precipitating action being exerted under a superatmospheric pressure below the condensation pressure of said gaseous treating agent at the treating temperature, said quantity being sufficient to cause the

formation of two liquid oil-containing phases of different specific gravities, and separating one phase from another.

2. The process of claim 1 in which the gaseous treating agent is natural gas.

3. The process of claim 1 in which the treating temperature is above the critical temperature of the gaseous treating agent.

4. In a process of separating a hydrocarbon oil into fractions having different properties, the steps of dissolving the oil in a liquid diluent for said oil, subjecting the resulting solution to the precipitating action of a quantity of a gaseous hydrocarbon treating agent consisting substantially of at least one of the hydrocarbons having less than three carbon atoms per molecule, said precipitating action being exerted under a superatmospheric pressure below the condensation pressure of said gaseous treating agent at the treating temperature, said quantity being sufficient to cause the formation of two liquid oil-containing phases of different specific gravities, and separating one phase from another.

5. In a process of separating a hydrocarbon oil into fractions having different properties the steps of dissolving the oil in a liquid hydrocarbon diluent having more than two carbon atoms per molecule, introducing into the resulting solution a quantity of a gaseous hydrocarbon treating agent consisting substantially of at least one of the hydrocarbons having less than three carbon atoms per molecule under a superatmospheric pressure below the condensation pressure of said gaseous treating agent at the treating temperature, said quantity being sufficient to cause the formation of two liquid oil-containing phases of different specific gravities, and separating one phase from another.

6. In a process of separating a hydrocarbon oil into fractions having different properties the steps of dissolving the oil in a liquid naphthenic solvent, introducing into the resulting solution a quantity of a gaseous hydrocarbon treating agent consisting substantially of at least one of the hydrocarbons having less than three carbon atoms per molecule under a superatmospheric pressure below the condensation pressure of said gaseous treating agent at the treating temperature, said quantity being sufficient to cause the formation of two liquid oil-containing phases of different specific gravities, and separating one phase from another.

7. In a process of separating a hydrocarbon oil into fractions having different properties, the steps of subjecting the oil to the precipitating action of a quantity of a gaseous hydrocarbon treating agent consisting substantially of at least one of the hydrocarbons having less than three carbon atoms per molecule, said precipitating action being exerted under a superatmospheric pressure below the condensation pressure of said gaseous treating agent at the treating temperature, said quantity being sufficient to cause the formation of two liquid oil-containing phases of different specific gravities, separating one phase from another, subjecting the separated liquid phase of lower specific gravity to the precipitating action of another quantity of a gaseous hydrocarbon treating agent consisting substantially of at least one of the hydrocarbons having less than three carbon atoms per molecule, said precipitating action being exerted under a superatmospheric pressure below the condensation pressure of said gaseous treating agent at the treating temperature, said second quanti-

ty of the treating agent being sufficient to cause the formation of two liquid oil-containing phases of different specific gravities, and separating one phase from another.

8. In a process of separating a hydrocarbon oil into fractions having different properties, the steps of subjecting the oil to the precipitating action of a quantity of a gaseous hydrocarbon treating agent consisting substantially of at least one of the hydrocarbons having less than three carbon atoms per molecule, said precipitating action being exerted under superatmospheric pressure and at a temperature above the critical temperature of the gaseous treating agent, said quantity being sufficient to cause the formation of two liquid oil-containing phases of different specific gravities, and separating one phase from another.

9. In a process of separating a hydrocarbon oil into fractions having different properties, the steps of subjecting the oil to the precipitating action of a quantity of a gaseous hydrocarbon treating agent consisting substantially of at least one of the hydrocarbons having less than three carbon atoms per molecule, said precipitating action being exerted under a pressure and at a temperature above the critical pressure and critical temperature, respectively, of the gaseous treating agent, said quantity being sufficient to cause the formation of two liquid oil-containing phases of different specific gravities, and separating said liquid phases one from the other.

10. In a process of separating a hydrocarbon oil into fractions having different properties, the steps of subjecting the oil to the precipitating action of a quantity of a normally gaseous hydrocarbon treating agent, said precipitating action being exerted under a pressure and at a temperature above the critical pressure and critical temperature, respectively, of the gaseous treating agent, said quantity being sufficient to cause the formation of two liquid oil-containing phases of different specific gravities, and separating said liquid phases one from the other.

11. In a process of separating a hydrocarbon oil into fractions having different properties, the steps of subjecting the oil to the precipitating action of a quantity of a gasiform light hydrocarbon treating agent, said precipitating action being exerted under a pressure and at a temperature above the critical pressure and critical temperature, respectively, of the gasiform treating agent, said quantity being sufficient to cause the formation of two liquid oil-containing phases of different specific gravities, and separating said liquid phases one from the other.

12. In a process of separating a hydrocarbon oil into fractions having different properties, the steps of subjecting the oil to the precipitating action of a quantity of a gaseous hydrocarbon treating agent consisting substantially of at least one of the hydrocarbons having less than three carbon atoms per molecule, said precipitating action being exerted at progressively varying pressures above the critical pressure of the gaseous treating agent and at a temperature above the critical temperature of the gaseous treating agent, said quantity being sufficient to cause the formation of two liquid oil-containing phases of different specific gravities, and separating said liquid phases one from the other.

13. In a process of separating a hydrocarbon oil into fractions having different properties, the steps of subjecting the oil to the precipitating action of a quantity of a gaseous hydrocarbon

treating agent consisting substantially of at least one of the hydrocarbons having less than three carbon atoms per molecule in the presence of a liquid naphthenic solvent, said precipitating action being exerted under a pressure and at a temperature above the critical pressure and critical temperature, respectively, of the gaseous treating agent, said quantity being sufficient to cause the formation of two liquid oil-containing phases of different specific gravities, and separating said liquid phases one from the other.

14. Process for separating hydrocarbon material into constituent parts which comprises extracting the hydrocarbon material with a normally liquefiable gaseous hydrocarbon solvent at a temperature above the critical temperature of the liquefiable hydrocarbon solvent and varying the density of the liquefiable hydrocarbon solvent by a progressive change in pressure and by the addition to the liquefiable hydrocarbon sol-

vent of a substance miscible therewith and capable of changing its density.

15. Process according to claim 14 in which the substance added to change the density is a non-hydrocarbon substance.

16. A process for separating a mineral oil containing a normally gaseous hydrocarbon and normally liquid hydrocarbons into constituent parts comprising the steps of varying the density of the normally gaseous hydrocarbons and precipitating normally liquid hydrocarbons to form a liquid phase heavier than said material, by a change in pressure without the addition of heat at a temperature above the critical temperature of the normally gaseous hydrocarbon, and separating said heavier liquid phase from the unprecipitated portion of said hydrocarbon material.
